UNITED STATES PATENT OFFICE.

VICTOR O. KEYS, OF VERSAILLES, KENTUCKY.

COIN-CONTAINER.

1,365,412.

Specification of Letters Patent. Patented Jan. 11, 1921.

Application filed May 15, 1920. Serial No. 381,697.

To all whom it may concern:

Be it known that I, VICTOR O. KEYS, a citizen of the United States, residing at Versailles, in the county of Woodford and 5 State of Kentucky, have invented certain new and useful Improvements in Coin-Containers, of which the following is a specification, reference being had to the accompanying drawings.

10 This invention relates to coin containers and particularly to a coin container for use by bank depositors, and bank employees.

The old method used by bank depositors, consists of placing the coin in a sack or like 15 receptacle, and when the coin is deposited in the bank it is necessary for the clerk to sort each coin according to its denomination and then count the same. This requires considerable time regardless of whether 20 there is a small amount of coin or a large amount of coin, and there is always danger of mistakes being made in the counting in view of the confusion caused by the mixing of the coins.

25 It is therefore an object of the invention to provide a coin container which is simple and compact in form capable of being conveniently carried by anyone and constructed to maintain the various denominations of 30 the coin in separate compartments, so that when the depositor places the money in the bank he can hand the entire container to the clerk, thereby facilitating the work of the clerk and saving time for himself.

35 Another object is to provide a device of this character wherein the drawer of the container is maintained at all times in an inclined position so as to hold the coins in the drawer on a slight incline and thereby 40 prevent them from falling to the bottom of the drawer.

Another object of the invention is to provide a container of this character wherein the front portion of the casing of the container serves as means for holding the drawer in an inclined position with respect to the bottom of the casing, and also for closing the end of the casing.

A still further object of the invention is 45 to provide a device of this character wherein the plate for closing the open end of the casing is extended beyond the edges of the drawer, and permits the drawer to coöperate with the upper portion of the casing to provide a compartment for the reception of 50 bills, checks and the like.

With these and other objects in view, the invention consists in the improved construction and arrangement of parts to be herein-after more particularly described, fully 60 claimed and illustrated in the accompanying drawings, in which:

Figure 1 is a perspective view of a coin container constructed in accordance with an embodiment of the invention, 65

Fig. 2 is a longitudinal sectional view,

Fig. 3 is a section taken on line 3—3 of Fig. 2, and

Fig. 4 is a fragmentary sectional view of the drawer. 70

Referring to the drawings, 5 designates a coin container comprising a casing including a bottom 6, sides 7, a top 9 and ends 10 and 11. Each of the sides 7 has its upper portion inclined from the end 10 to the end 11, the top 9 inclining accordingly, that is, from the end 10 to the end 11. The end 10 of the casing is closed while the end 11 is open, the edge 12 of the bottom 6 projecting beyond the open end 11, the purpose 80 of which will be hereinafter described. The ends of the side members 7 are vertically disposed in parallel relation to each other.

In connection with the casing, a coin drawer 13 is used, said drawer being provided with a plurality of channels 14, each channel being of a size to receive different denominations of coins from one cent to a silver dollar, etc., each channel permitting a collection of each denomination to be maintained in the proper stack thereby eliminating the necessity of sorting the coin in the process of counting. The end 15 of the drawer 13 is canted toward the bottom of 90

said drawer, the canted end being secured to a plate 16. This plate is of a size sufficient to close the open end 11 of the casing, and therefore has its edges extending beyond the edges of the ends 15 of the drawer. It will be noted that the canted end of the drawer 13 is secured to the plate 16 slightly below the longitudinal center of the plate. This causes the end 15 of the drawer to be raised in spaced relation to the bottom of the casing according to the distance between the lower 105 edge of the plates and the bottom of the drawer. It also causes the lower surface of the end 18 of the drawer to engage the bottom of the casing. In this way the drawer is maintained in an inclined position so as to 110 prevent the coins from being set in a position parallel to the vertical. This also pre-

vents the coins from swinging toward the bottom, as they are inclined in a perfect stack toward the end 18 by the position of the plate 16. Furthermore, in view of the 5 canted end 15, the plate 16 is maintained in a vertical position regardless of the fact that the drawer is deposited in an inclined position. In view of this, the plate 16 can be utilized to close the open end 11 of the casing without interfering with the inclined 10 position of the drawer.

The upper portion of the plate 16 extends quite a distance above the upper edge of the drawer, and is intended to engage the edge 15 of the top 9 adjacent the open end 11. The drawer 13 also coöperates with the top 9 of the casing to provide a compartment in which bills, checks, bank books and like articles may be deposited on top of the coin, the 20 upper portion of the plate 16 serving to close the compartment. When it is desired to close the casing, the drawer is moved inwardly thereof so as to permit the lower edge of the plate 16 to engage the edge 12 of the bottom 6. This brings the inner edges 25 of the ends and upper portion of the plate into engagement with the edges of the sides and top of the casing, and in view of the weight provided by the coins in the drawer, 30 this arrangement serves as a temporary lock to prevent accidental disengagement of the drawer from the casing and also to render it neat in appearance and capable of being readily carried without danger of spilling 35 the contents of the drawer.

It will thus be seen that this invention provides a novel device for use by bankers, and large business houses as means for conveying metal currency to the bank. Considerable time is saved as well as mistakes prevented in the counting of the coins by the 40 use of this container. It also serves as an efficient cash drawer as it holds the coins ac-

cording to the denomination thereof in the much desired inclined position so that they 45 may be readily removed from the drawer. In addition to this it provides additional room for carrying paper currency, bills and the like in the upper portion of the casing. It will also be noted that when the drawer 50 is removed from the casing it is still maintained in its inclined position by means of the plate 16 so that the device may be used as a coin holder for cashiers in making change, etc., thereby eliminating the necessity 55 of a separate holder. If desired, the device can be made from cheap material such as cardboard and used as an advertising medium by banks, in addition to facilitating the work of the bank by providing each depositor with a coin container wherein a cash deposit can be readily made and instantly 60 counted without the necessity of sorting the coins.

What I claim is:—

A coin container comprising a casing having a bottom, inclined top and sides and an open end, said sides and top inclining toward the open end, the edge of said bottom extending beyond the open end, a drawer in 70 said casing, one end of said drawer being canted, a plate secured to said canted end, said end maintaining the plate in a vertical position, the opposite end portion of the drawer having its lower surface slidably engaged with the bottom of the casing, whereby 75 said drawer is maintained in an inclined position with respect to the casing and in spaced parallel relation to the top of the casing, said plate being arranged to close the 80 open end of the casing when the plate is supported by the edge of the bottom of the casing.

In testimony whereof I hereunto affix my signature.

VICTOR O. KEYS.
